United States Patent Office

Des. 193,026
Patented June 12, 1962

193,026

KEY CUTTER

Charles Rossetti, Lausanne, Switzerland, assignor to
Simeca S.A., Vevey, Switzerland

Filed Feb. 14, 1961, Ser. No. 63,936

Term of patent 14 years

(Cl. D55—1)

FIG. 1

FIG. 2

FIG. 3

FIG. 4

FIG. 5

FIGURE 1 is a front perspective view of a key cutter showing my new design.

FIGURE 2 is a side elevation thereof;

FIGURE 3 is a top plan view thereof with the lever handle omitted;

FIGURE 4 is a front end elevation thereof;

FIGURE 5 is a rear end elevation thereof.

I claim:

The ornamental design for a key cutter, substantially as shown.
